UNITED STATES PATENT OFFICE.

WILLIAM SCHALK, OF WEST ALLIS, WISCONSIN.

SHIPPING-BOX.

1,316,194.

Specification of Letters Patent. Patented Sept. 16, 1919.

Application filed June 16, 1916. Serial No. 103,921.

To all whom it may concern:

Be it known that I, WILLIAM SCHALK, a citizen of the United States, and resident of West Allis, in the county of Milwaukee and State of Wisconsin, have invented new and useful Improvements in Shipping-Boxes, of which the following is a description, reference being had to the accompanying drawings, which are a part of this specification.

10 The invention relates to shipping boxes or cases.

The invention is designed more particularly to provide a shipping box which may be made of parts readily assembled together for use as a container and which may be readily knocked down so as to occupy a small space when it is returned to the shipper.

One of the uses of a box of this kind is in the shipping of leaf tobacco. Formerly tobacco was shipped in boxes which could not be readily opened for inspection and the present invention is designed to obviate this difficulty by providing a foldable box, in which the ends, sides and top of the box 25 may be thrown down and out of the way to permit a thorough inspection of the tobacco. Furthermore while it is necessary to have a strong box for shipping purposes it is also necessary that in some classes of goods, such 30 as tobacco, to prevent its coming in contact with any metallic reinforcement on the box and I have provided for this by so constructing the box as to provide an interior lining of wood or other suitable material forming the box sections and by binding and securing said sections by metal reinforcements on the outside of the box.

The invention further designs to provide a box made up of foldable sections, each of 40 said sections being provided with metallic reinforcements, which reinforcements are provided with detachable hinges, the sections of the box being secured together by fastening means passing through the reinforcements.

The invention further designs to provide a new and improved form of shipping box.

The invention consists in the several features hereinafter set forth and more particularly defined by claims at the conclusion hereof.

In the drawings:

Figure 1 is a view of one side of the box, parts being broken away and parts being 55 shown in section;

Fig. 2 is an end view of the box;

Fig. 3 is a plan view of the box, the cover being raised and parts being broken away;

Fig. 4 is a section taken on the line 4—4 of Fig. 1;

Fig. 5 is a section taken on the line 5—5 of Fig. 2;

Fig. 6 is a section taken on the line 6—6 of Fig. 2;

Fig. 7 is a detail sectional view of one of 65 the detachable hinges for the sections;

Fig. 8 is a view of the box in assembled unfolded condition;

Fig. 9 is a view of the box similar to Fig. 8 with the sections of the box separated from 70 each other;

Fig. 10 is a plan view of the box in knocked down condition; and

Fig. 11 is a section taken on the line 11—11 of Fig. 10.

The box comprises a bottom 7, sides 8 hinged thereto, top 9 hinged to one of the sides, ends 10 hinged at either end of the bottom 7, means for reinforcing and connecting the sections in assembled condition, and 80 means for securing the sections in knocked down condition.

The top, bottom and sides are preferably made of solid pieces of wood or other material while the ends are made of a plurality 85 of pieces 11 spaced apart to provide for air spaces as in the use of the boxes in connection with tobacco it is necessary that proper ventilation be provided.

The bottom 7 is provided with a plurality 90 of reinforcing members or bars 12 preferably of sheet metal which are secured within recesses 13 extending transversely of the bottom on the outside thereof. The sides 8 are likewise provided with a plurality of reinforcing members 14 similar to the bars 12 and which are secured within transverse recesses 15 on the outer side of said sides. Detachable hinge connections are provided between the bottom 7 and the sides 8 and each 100

of these consist of a detachable hinge connection between the aligned reinforcing members 12 and 14 on the bottom and sides of the box respectively. Each of these detachable hinges is formed as shown more particularly in Fig. 7 by extending the members 14 outwardly from the sides 8 to form hooked ears 14' for receiving a hinge pin 8' and the ends of the members 12 are bent up 105 within recess portions 7' to form hooks 12' 110

within recess portions 7' to form hooks 12' 110

for detachably engaging the pin 8' to form a detachable hinge connection between the bottom and the sides of the box. Though the hinge connection has been described with reference to the bottom and sides of the box, this description applies also to the detachable hinge connections between the bottom and the ends of the box and between the top and one of the sides of the box hereinafter described. The top 9 is also provided with bars 17 secured within transverse recesses 18 on the outside thereof and is hinged to one of the sides 8 through the detachable hinge connections previously described. Thus it will be noted that the reinforcing members or bars 12, 14 and 17 form continuous bands extending around the top, bottom and sides of the box and are detachably secured to each other so the parts of the box may be separated and packed in knockdown condition.

The pieces 11 are connected together to form the end sections 10 by a plurality of reinforcing bars 19 which are secured in recesses 20 in said pieces extending transversely thereof and these bars are hingedly secured to the extensions 21 through detachable hinge connections previously described. The extensions 21 are riveted to the bars 12 and extend at an angle thereto.

By reason of the detachable hinges between the sections they may be readily disconnected and compactly packed in knockdown form, as shown in Fig. 11, and secured in this condition by bolts 15 which pass through apertures 16 in the sections and engage in nuts 16' seated within the bottom section 7 near the outside thereof. In this way the parts of the box are compactly secured to occupy small space for return to the shipper. When the box is packed the bolts 15 are passed through holes 15' in the top 9 and thence through vertical holes 10' in the ends 10 and are secured to said sides 45 by nuts 11' seated at the lower ends of the holes 10' within the ends 10. Thus the bolts 15 serve to retain the sections both in knockdown and assembled positions. It will be noted that the hinge hooks 12' on the bottom 7 and top 9 are set into recesses 7' in the edges thereof so that they will flush with said edges, as shown more particularly in Fig. 7.

Extensions 22 are riveted to the bars 19 and extend outwardly from the ends of the box and have apertures 23 therein.

The end edges of the sides 8 have recesses 24 therein to receive the extensions 22 of the bars and apertures 25 adjacent said recesses and extending lengthwise of the sides to a position adjacent the transverse bands 14. Threaded nuts 26 having lugs 27 thereon are fastened to the bands 14 adjacent said apertures 25, the lugs 27 permitting the nuts 26 to be riveted to the

bands as shown in Fig. 4. Bolts or other suitable fastening means 28 pass through the apertures 23, 25 and into the nuts 26 which being embedded in recesses 29 in the sides 8 connect the bands 22 with the bands 14 and consequently the ends 10 to the sides 8.

The top 9 has apertures 30 adjacent apertures 31 in the band 17 which apertures are adapted to receive screw bolts 32 or other suitable fastening means which pass through threaded plates 33 secured in the recesses 34 in the edge of one of the side sections 8 and riveted to the ends of the bars 14. The screw bolts 32 thus serve to connect the bands 17 and 14 together and also secure the top to the side.

Strips 35 are secured on the inner side of the bottom 7 adjacent the ends and serve as stops for the ends 10 when they are in position and triangular shaped stop strips 36 on the ends 10 and sides 8 serve to keep the ends and sides in proper position when the box is assembled.

In the use of the box the sides 8 are turned up against the bottom 7 and the ends 10 are secured to the sides by the bolts 28 which pass through the extensions 22 and into the nuts 26 in the sides 8. The box is then packed and the top is then secured to the opposite side section 8 by the bolts 32. If it is desired to inspect the contents of the box the bolts 28 are removed and the ends dropped down and the bolts 32 removed and the top and sides dropped down leaving the contents of the box resting upon the bottom 7 open to inspection.

After the shipment has been made the consignee detaches the hinged sections as previously described secures them together in stacked relation and in this condition the box is returned to the shipper.

From the foregoing description it will be noted that the interior of the box is wholly of wood or other suitable material and that the metal reinforcement also serves to detachably secure the sections of the box together so that the box may be readily inspected and also returned to the shipper in knockdown condition.

What I claim as my invention is:

1. A knockdown box, comprising a foldable top, bottom, side and end sections, each having apertures therein adapted to register when the sections are separated, nuts carried by one of the sections in line with its apertures, reinforcing means forming a skeleton frame comprising metal bands secured to said sections, readily detachable hinge connections between the meeting ends of said bands, means for fastening the section in assembled position including bolts passing through certain of the sections, said bolts being removable on the separation of the sections and adapted to pass through said apertures and be secured to said nuts to

secure said sections in stacked knockdown condition.

2. A knockdown box, comprising foldable top, bottom, side and end sections having apertures therein adapted to register when the sections are separated, a skeleton reinforcing frame including metal bands secured in recesses, formed transversely in said sections, 25 one end of each adjacent meeting end of the metal bands being recessed and bent to provide spaced ears, a hinge pin fixed in said ears, the other end of each adjacent meeting end of the metal bands being hinged and 30 adapted to engage the hinge pin to provide a detachable hinge connection, capable of detachment when the sections are swung from assembled position, fastening means passing through the bands on adjacent portions to secure the box in assembled position, and bolts passing through certain of the sections for securing them in assembled relation and passing through the apertures in each section when the same are separated 35 whereby to secure them in knockdown condition. 40
3. A knockdown box, comprising foldable top, bottom, side and end sections having

apertures therein, a skeleton reinforcing frame including metal bands secured in recesses, formed transversely in said sections, 25 one end of each adjacent meeting end of the metal bands being recessed and bent to provide spaced ears, a hinge pin fixed in said ears, the other end of each adjacent meeting end of the metal bands being hinged and 30 adapted to engage the hinge pin to provide a detachable hinge connection, capable of detachment when the sections are swung from assembled position, fastening means passing through the bands on adjacent portions to secure the box in assembled position, and bolts passing through certain of the sections for securing them in assembled relation and passing through the apertures in each section when the same are separated 35 whereby to secure them in knockdown condition. 40

In testimony whereof, I affix my signature.

WILLIAM SCHALK.
